ABSTRACT

A coil device includes: a drum core having first and second flange portions and a winding core portion therebetween; a coil wound around the core portion; a plate core connected to first and second flange portions first and second flange surfaces at a first direction side; a first electrode terminal on the first flange portion, one coil end portion electrically connected on the first electrode terminal; and a second electrode terminal on the second flange portion, the other coil end portion electrically connected on the second electrode terminal. The plate core has a first and second projecting portions respectively protruding toward the first and second flange surfaces and having first and second flat surfaces facing the first and second flange surfaces. The drum core and the plate core are connected by abutting and bonding the first and second flange surfaces against the first and second flat surfaces.

COIL DEVICE

BACKGROUND OF THE INVENTION

1. Field of the Invention

The present invention relates to a coil device that uses a core which is a combination of a plate core and a drum core.

2. Description of the Related Art

A coil device that uses a core which is a combination of a plate core and a drum core has been proposed as a surface-mountable chip-type coil device. The plate core is bonded with an adhesive or the like to a flange portion of the drum core. The plate core of the related art has a simple plate shape, is connected to two flange portions of the drum core, and forms a closed magnetic circuit together with the drum core (see JP 2002-329618 A).

SUMMARY OF THE INVENTION

However, in the core having the shape of the related art, a problematic decline in the bondability between the drum core and the plate core arises due to the material of the core or the like. For example, the bondability tends to decline in a case where the material of the plate core is not ferrite and the plate core is including metal particles, such as a metal core or an alloy core.

The invention has been made in view of such circumstances, and an object of the invention is to provide a coil device having satisfactory bondability between a plate core and a drum core.

In order to achieve the above object, a coil device according to the invention includes:

- a drum core having a first flange portion, a second flange portion and a winding core portion disposed between the first and second flange portions;
- a coil wound around the winding core portion;
- a plate core connected to a first flange surface of the first flange portion at a first direction side and a second flange surface of the second flange portion at the first direction side;
- a first electrode terminal provided on the first flange portion, one end portion of the coil being electrically connected on the first electrode terminal; and
- a second electrode terminal provided on the second flange portion, the other end portion of the coil being electrically connected on the second electrode terminal, wherein

the plate core has a first projecting portion protruding toward the first flange surface and having a first flat surface facing the first flange surface and a second projecting portion protruding toward the second flange surface and having a second flat surface facing the second flange surface, and

the drum core and the plate core are connected by abutting and bonding the first flange surface against the first flat surface and by abutting and bonding the second flange surface against the second flat surface.

The plate core of the coil device according to the invention has the first projecting portion and the second projecting portion. The plate core is bonded to the first flange portion and the second flange portion of the drum core by the first flat surface of the first projecting portion butting against the first flange surface and the second flat surface of the second projecting portion butting against the second flange surface.

2

By the plate core having the first projecting portion and the second projecting portion, a surface suitable for bonding is formed in the first projecting portion and the second projecting portion as compared with a flat plate core of the related art. Accordingly, in the coil device according to the invention, the plate core is bonded to the drum core via the first projecting portion and the second projecting portion, and thus the bondability between the plate core and the drum core is satisfactory.

10 In addition, for example, a length of the plate core may be shorter than a length of the drum core along a winding axis direction.

15 By the length of the plate core being shorter than the length of the drum core, an adhesive easily spreads to the part that is outside the first flat surface in the first projecting portion and the part that is outside the second flat surface in the second projecting portion, and thus the coil device has satisfactory bondability between the plate core and the drum core.

20 In addition, for example, a first cured-adhesive portion bonding the first flange surface and the first flat surface may be also in contact with a first wall surface extending from the first flat surface of the first projecting portion in a direction away from the first flange surface, and

25 a second cured-adhesive portion bonding the second flange surface and the second flat surface may be also in contact with a second wall surface extending from the second flat surface of the second projecting portion in a direction away from the second flange surface.

30 The first wall surface in the first projecting portion and the second wall surface in the second projecting portion have a surface denser than the first flat surface and the second flat surface and are satisfactorily bondable to the adhesive.

35 Accordingly, by the cured-adhesive portion being in contact with the first wall surface and the second wall surface, the coil device is capable of improving the bondability between the plate core and the drum core.

40 In addition, for example, the first wall surface may have a first inner wall surface extending from the first flat surface at a side close to the second flat surface and the first cured-adhesive portion is in contact with the first inner wall surface, and

45 the second wall surface may have a second inner wall surface extending from the second flat surface at a side close to the first flat surface and the second cured-adhesive portion is in contact with the second inner wall surface.

50 The first inner wall surface and the second inner wall surface are wall surfaces positioned on the central recessed portion side of the first projecting portion and the second projecting portion, and the wall surfaces in particular tend to form a dense surface in the first projecting portion and the second projecting portion. Accordingly, in the coil device in

55 which the cured-adhesive portion is in contact with the first inner wall surface and the second inner wall surface, the bondability between the plate core and the drum core can be effectively improved. In addition, in the coil device, the cured-adhesive portion spreads to the center side of the plate

60 core with respect to the first projecting portion and the second projecting portion, and thus the external dimension of the coil device is not affected even in the event of adhesion area expansion to such a part. Accordingly, the coil device has little external dimensional manufacturing deviation and it is possible to realize the coil device in which the bondability between the plate core and the drum core is satisfactory.

In addition, for example, the first wall surface may have a first outer wall surface extending from the first flat surface at a side far from the second flat surface and the first cured-adhesive portion is in contact with the first outer wall surface, and

the second wall surface may have a second outer wall surface extending from the second flat surface at a side far from the first flat surface and the second cured-adhesive portion is in contact with the second outer wall surface.

The first outer wall surface and the second outer wall surface are wall surfaces positioned outside the first flat surface and the second flat surface in the first projecting portion and the second projecting portion. The wall surfaces tend to form a surface denser than the first flat surface and the second flat surface. Accordingly, in the coil device in which the cured-adhesive portion is in contact with the first outer wall surface and the second outer wall surface, the bondability between the plate core and the drum core can be effectively improved. In addition, in the coil device in which the cured-adhesive portion is in contact with the first outer wall surface and the second outer wall surface, both end portions of the plate core or the surroundings thereof can be coated with an adhesive, and thus the bondability between the plate core and the drum core is satisfactory.

In addition, for example, the plate core may be including metal particles.

The surface tends to be rougher in a case where the plate core is including metal particles, such as a metal core or an alloy core than in a case where the plate core is a ferrite core. However, even such a plate core has satisfactory bondability with respect to the drum core by having the first projecting portion and the second projecting portion.

In addition, for example, the drum core may be a ferrite core.

In the case of the shape according to the related art, a decline in bondability tends to arise in a case where a metal plate core and a ferrite drum core are bonded. However, the coil device is satisfactory in terms of the bondability between the plate core and the drum core by the plate core having the first projecting portion and the second projecting portion.

BRIEF DESCRIPTION OF THE DRAWINGS

FIG. 1 is a perspective view of a coil device according to an embodiment of the invention;

FIG. 2 is an exploded perspective view of the coil device illustrated in FIG. 1;

FIG. 3 is a front view of a plate core included in the coil device illustrated in FIG. 1;

FIG. 4 is a bottom view of the plate core included in the coil device illustrated in FIG. 1;

FIG. 5 is a cross-sectional view of the coil device illustrated in FIG. 1;

FIG. 6 is a partially enlarged cross-sectional view in which a part of FIG. 5 is enlarged; and

FIG. 7 is a cross-sectional view of a coil device according to another embodiment of the invention.

DETAILED DESCRIPTION OF THE PREFERRED EMBODIMENTS

FIG. 1 is a perspective view in which a coil device 10 according to an embodiment of the invention is seen obliquely from above. The coil device 10 has a drum core 20, a coil 30, a plate core 40, a first electrode terminal 74,

a second electrode terminal 76, and the like. The coil device 10 has a substantially rectangular parallelepiped outer shape. The coil device 10 is surface-mounted onto a mounting substrate by, for example, an adsorption nozzle of a mounting machine adsorbing, holding, and transporting the upper surface of the plate core 40. However, the coil device 10 is not limited to being surface-mounted.

FIG. 2 is an exploded perspective view of the coil device 10 illustrated in FIG. 1. As illustrated in FIG. 2, the core of the coil device 10 is configured by the drum core 20 and the plate core 40 being bonded. The coil device 10 has a first cured-adhesive portion 64 and a second cured-adhesive portion 66, which are formed by the adhesive that bonds the plate core 40 and the drum core 20 being hardened.

Although examples of the adhesive that becomes the first cured-adhesive portion 64 and the second cured-adhesive portion 66 after the hardening include an epoxy-based adhesive, a non-epoxy-based adhesive may also be used. It should be noted that the shapes of the first cured-adhesive portion 64 and the second cured-adhesive portion 66 are schematically illustrated in FIG. 2. The shapes of the first cured-adhesive portion 64, the second cured-adhesive portion 66, and the surroundings of the first cured-adhesive portion 64 and the second cured-adhesive portion 66 will be described in detail later with reference to FIGS. 5 and 6.

As illustrated in FIG. 2, the drum core 20 has a winding core portion 22 and a first flange portion 24 and a second flange portion 26 disposed on both sides across the winding core portion 22. The coil 30 is wound around the winding core portion 22. It should be noted that the X-axis direction in the description of the coil device 10 is the winding axis direction of the coil 30, the Z-axis direction in the description is the direction in which the drum core 20 and the plate core 40 are bonded, and the Y-axis direction in the description is orthogonal to the X-axis direction and the Z-axis direction as illustrated in FIGS. 1 and 2.

Although the cross section of the winding core portion 22 that is orthogonal to the winding axis direction is rectangular, the cross-sectional shape of the winding core portion 22 is not limited thereto and may be a circular shape, an elliptical shape, or another shape. As in the case of the winding core portion 22, the cross sections of the first flange portion 24 and the second flange portion 26 that are orthogonal to the winding axis direction are rectangular. However, the first flange portion 24 and the second flange portion 26 are larger in cross-sectional area than the winding core portion 22 with regard to the cross sections orthogonal to the winding axis direction. The first flange portion 24 and the second flange portion 26 protrude with respect to the winding core portion 22 with regard to the direction that is orthogonal to the winding axis direction.

The outer shape of the plate core 40 is a substantially rectangular plate shape or a substantially rectangular parallelepiped shape. The plate core 40 is connected to the first flange portion 24 and the second flange portion 26 of the drum core 20. The plate core 40 is connected to a first flange surface 24a and a second flange surface 26a, which are surfaces of the first flange portion 24 and the second flange portion 26. The first flange surface 24a and the second flange surface 26a are on the Z-axis positive direction side, which is a first direction side. The shape of the plate core 40 will be described in detail later.

The first flange portion 24 is provided with the first electrode terminal 74 to which a first end portion 34, which is one end portion of the coil 30, is electrically connected. Although the first electrode terminal 74 is provided on a flange lower surface 24b, which is on the side that is

opposite to the first flange surface 24a, as illustrated in FIG. 5, the installation position of the first electrode terminal 74 is not limited thereto. The first electrode terminal 74 may be provided so as to be continuous with another surface of the first flange portion 24 or a plurality of surfaces of the first flange portion 24.

The second flange portion 26 is provided with the second electrode terminal 76 to which a second end portion 36, which is the other end portion of the coil 30, is electrically connected. Although the second electrode terminal 76 is provided on a flange lower surface 26b, which is on the side that is opposite to the second flange surface 26a, as illustrated in FIG. 5, the installation position of the second electrode terminal 76 is not limited thereto. The second electrode terminal 76 may be provided so as to be continuous with another surface of the second flange portion 26 or a plurality of surfaces of the second flange portion 26.

The drum core 20 and the plate core 40 illustrated in FIG. 2 are made of, for example, a magnetic material. Although the drum core 20 and the plate core 40 may be made of the same type of material, the drum core 20 and the plate core 40 may also be made of different materials. In the coil device 10 according to the embodiment, the plate core 40 is a metal core or an alloy core such as pure iron and Fe—Ni, Fe—Si, Fe—Si—Al, and Fe—Si—Cr alloys.

The plate core 40 is made by, for example, soft magnetic metal powder being mixed with a binder or the like, formed, and fired. Since the plate core 40 is a metal core or an alloy core, the magnetic saturation characteristics of the coil device 10 can be improved. It should be noted that the soft magnetic metal particles contained in the plate core 40 preferably form an insulating film of an oxide such as chromium oxide and the plate core 40 has a high resistance value and is capable of reducing core loss although the plate core 40 is a metal core or an alloy core. Alternatively, the plate core 40 may be a ferrite core.

In the coil device 10 according to the embodiment, the drum core 20 is a ferrite core. However, the drum core 20 is not limited to the ferrite core and the drum core 20 may be a metal core or an alloy core as in the case of the plate core 40. The drum core 20 is obtained by, for example, a ferrite sintered body being made by means of ferrite powder such as Mn—Zn-based ferrite and Ni—Zn-based ferrite.

Since the drum core 20 is made of, for example, a ferrite formed body that does not substantially contain a binder, it is possible to prevent a problem such as void generation in the drum core 20. In addition, by the drum core 20 being a ferrite core, it is possible to realize a core having a high resistance value and reduce core loss. In addition, by the plate core 40 being a metal core or an alloy core and the drum core 20 being a ferrite core, it is possible to realize the coil device 10 having satisfactory magnetic saturation characteristics and little core loss.

The first electrode terminal 74 and the second electrode terminal 76 illustrated in FIG. 5, which is a cross-sectional view, are made by, for example, an electrode material such as Ag, Ni, and Sn being applied to the first flange portion 24 and the second flange portion 26 and baking or plating-based film formation being performed. However, the first electrode terminal 74 and the second electrode terminal 76 are not limited thereto. For example, the first electrode terminal 74 and the second electrode terminal 76 may be made by metal plate attachment to the first flange portion 24 and the second flange portion 26.

For example, a coated conducting wire or the like constitutes the coil 30 illustrated in FIG. 1. The conducting wire constituting the coil 30 may be a stranded wire or a single

wire. As illustrated in FIG. 5, the coil 30 is wound in one layer around the winding core portion 22. Alternatively, the coil 30 may be wound in multiple layers around the winding core portion 22. In addition, the first end portion 34 and the second end portion 36 of the coil 30 are fixed by welding, soldering, or the like to the first electrode terminal 74 and the second electrode terminal 76.

FIG. 3 is a front view of the plate core 40 included in the coil device 10. FIG. 4 is a bottom view of the plate core 40. As illustrated in FIG. 3, the plate core 40 has a first projecting portion 44 and a second projecting portion 46. The first projecting portion 44 and the second projecting portion 46 are formed on the surface of the plate core 40 on the Z-axis negative direction side that faces the drum core 20. In addition, the first projecting portion 44 and the second projecting portion 46 are disposed on both sides of the plate core 40 in the X-axis direction (winding axis direction) and a recessed portion 48 is formed between the first projecting portion 44 and the second projecting portion 46. The recessed portion 48 is recessed to the Z-axis positive direction side with respect to the first projecting portion 44 and the second projecting portion 46.

As illustrated in FIG. 5, which is a cross-sectional view, the first projecting portion 44 protrudes toward the first flange surface 24a of the drum core 20. A first flat surface 44a, which is the tip surface of the first projecting portion 44, faces the first flange surface 24a. The second projecting portion 46 protrudes toward the second flange surface 26a of the drum core 20. A second flat surface 46a, which is the tip surface of the second projecting portion 46, faces the second flange surface 26a.

As illustrated in FIG. 5, the drum core 20 and the plate core 40 are bonded by the first flange surface 24a and the first flat surface 44a butting against each other and the second flange surface 26a and the second flat surface 46a butting against each other. The first cured-adhesive portion 64 is interposed between the first flange surface 24a and the first flat surface 44a. The second cured-adhesive portion 66 is interposed between the second flange surface 26a and the second flat surface 46a.

As illustrated in FIGS. 3 and 4, the first projecting portion 44 has a first wall surface 44b as well as the first flat surface 44a butting against the first flange surface 24a. The first wall surface 44b extends in an obliquely upward direction or an upward direction (Z-axis positive direction), which is a direction away from the first flange surface 24a from the first flat surface 44a. The first wall surface 44b has a first inner wall surface 44ba and a first outer wall surface 44bb. The first inner wall surface 44ba is connected to the first flat surface 44a on a side close to the second flat surface 46a (X-axis positive direction side). The first outer wall surface 44bb is connected to the first flat surface 44a on a side far from the second flat surface 46a (X-axis negative direction side).

In addition, the second projecting portion 46 has a second wall surface 46b as well as the second flat surface 46a butting against the second flange surface 26a. The second wall surface 46b extends in an obliquely upward direction or an upward direction (Z-axis positive direction), which is a direction away from the second flange surface 26a from the second flat surface 46a. The second wall surface 46b has a second inner wall surface 46ba and a second outer wall surface 46bb. The second inner wall surface 46ba is connected to the second flat surface 46a on a side close to the first flat surface 44a (X-axis negative direction side). The second outer wall surface 46bb is connected to the second

flat surface **46a** on a side far from the first flat surface **44a** (X-axis positive direction side).

As illustrated in FIG. 3, the first inner wall surface **44ba** and the second inner wall surface **46ba** are curved surfaces inclined to the center side of the plate core **40** in the winding axis direction (X-axis direction) and the first outer wall surface **44bb** and the second outer wall surface **46bb** are flat surfaces inclined to the outside of the plate core **40** in the winding axis direction (X-axis direction). The first inner wall surface **44ba** and the second inner wall surface **46ba** are connected by the recessed portion **48**.

As illustrated in FIG. 6, in which a part of FIG. 5 is enlarged, the first cured-adhesive portion **64** bonding the first flange surface **24a** and the first flat surface **44a** protrudes from the first flat surface **44a** and is in contact with the first wall surface **44b**. In other words, the part of the first cured-adhesive portion **64** that protrudes from the first flat surface **44a** to the center side of the plate core **40** is in contact with the first inner wall surface **44ba**. In addition, the part of the first cured-adhesive portion **64** that protrudes from the first flat surface **44a** to the outside of the plate core **40** is in contact with the first outer wall surface **44bb**.

As illustrated in FIG. 5, the second cured-adhesive portion **66** bonding the second flange surface **26a** and the second flat surface **46a** protrudes from the second flat surface **46a** and is in contact with the second wall surface **46b** as in the case of the first cured-adhesive portion **64**. In other words, the part of the second cured-adhesive portion **66** that protrudes from the second flat surface **46a** to the center side of the plate core **40** is in contact with the second inner wall surface **46ba**. In addition, the part of the second cured-adhesive portion **66** that protrudes from the second flat surface **46a** to the outside of the plate core **40** is in contact with the second outer wall surface **46bb**.

Here, by the plate core **40** having the first projecting portion **44** and the second projecting portion **46** as illustrated in FIGS. 3 and 4, the surface of the plate core **40** that faces the drum core **20** tends not only to increase in surface area but also to form a partially dense surface. In other words, the plate core **40** as illustrated in FIG. 3 is molded by means of a press mold moving in the Z-axis direction, which is the thickness direction of the plate core, and thus the first wall surface **44b** and the second wall surface **46b** not parallel to the first flat surface **44a** and the second flat surface **46a** tend to form a surface where the material constituting the core is densely disposed as compared with the first flat surface **44a** and the second flat surface **46a** orthogonal to the Z-axis direction.

In addition, of the first wall surface **44b** and the second wall surface **46b**, the first inner wall surface **44ba** and the second inner wall surface **46ba** close to the thin recessed portion **48** tend to be surfaces where the material is densely disposed as compared with the first outer wall surface **44bb** and the second outer wall surface **46bb**. It is conceivable that the density of such a surface is because the amount of movement of particles in the press mold increases in the direction of movement of the press mold and at a thin part and decreases in the direction perpendicular to the direction of movement of the press mold and at a thick part.

In the coil device **10**, the first projecting portion **44** and the second projecting portion **46** are provided at the part of bonding to the drum core **20** in the plate core **40**. As a result, a dense surface satisfactorily bondable to the first and second cured-adhesive portions **64** and **66** illustrated in FIG. 5 is disposed on the first projecting portion **44** and the second projecting portion **46**. Accordingly, the coil device **10** in which the first and second cured-adhesive portions **64**

and **66** are interposed between the first and second projecting portions **44** and **46** and the first and second flange surfaces **24a** and **26a** is satisfactory in terms of the bonding strength between the plate core **40** and the drum core **20**.

5 In addition, the first and second cured-adhesive portions **64** and **66** are in contact with the first wall surface **44b** and the second wall surface **46b**, where the dense surface formation tendency is particularly strong in the first projecting portion **44** and the second projecting portion **46**, and thus the 10 bonding strength between the plate core **40** and the drum core **20** is further improved. It should be noted that providing the first projecting portion **44** and the second projecting portion **46** is particularly effective for bonding strength improvement between the plate core **40** and the drum core **20** in a case where the plate core **40** is a metal core or an 15 alloy core.

In other words, the surface of the metal core or the alloy core tends to be rougher than the surface of a ferrite core such as sintered ferrite due to, for example, a large binder 20 amount of the formed body. Adhesive application to the rough metal or alloy core surface may result in a rapid removal of the solvent component of the adhesive from the surface, and then the strength of bonding by the cured-adhesive portion may be adversely affected. However, in the 25 plate core **40** of the coil device **10**, the dense surface is formed on the first projecting portion **44** and the second projecting portion **46**, and thus the loss of the solvent component of the adhesive during adhesion is suppressed and the first and second cured-adhesive portions **64** and **66** 30 exhibit suitable bonding strength.

Although the invention has been described with reference to the embodiment as described above, it is a matter of course that the invention is not limited to the above-described embodiment and includes many other embodiments, 35 examples, and modification examples. For example, the first wall surface **44b** and the second wall surface **46b** of the first projecting portion **44** and the second projecting portion **46** may extend in the upward direction (Z-axis positive direction) perpendicularly to the first flat surface **44a** and the second flat surface **46a** instead of being inclined surfaces 40 extending obliquely upward from the first flat surface **44a** and the second flat surface **46a** as illustrated in FIG. 3.

In addition, although the length of the plate core **40** along the winding axis direction (X-axis direction) is the same as the 45 length of the drum core **20** along the winding axis direction in the coil device **10** illustrated in FIG. 1, the plate core **40** and the drum core **20** may have different lengths. FIG. 7 is a cross-sectional view of a coil device **110** according to another embodiment. The coil device **110** differs from the coil device **10** according to the first embodiment in that a length **L1** of a plate core **140** along the winding axis direction is shorter than a length **L2** of the drum core **20** along the winding axis direction.

In the coil device **110** illustrated in FIG. 7, the entire first outer wall surface **44bb** and the entire second outer wall surface **46bb** are coated with a first cured-adhesive portion **164** and a second cured-adhesive portion **166**, respectively. In this manner, in the coil device **110**, the first cured-adhesive portion **164** and the second cured-adhesive portion **166** spread to the vicinity of the outside surface of the plate core **140** and the bonding strength between the plate core **140** and the drum core **20** is satisfactory.

In addition, the length **L1** of the plate core **140** is shorter than the length **L2** of the drum core **20** in the coil device **110**. 60 Accordingly, protrusion to the outside of the drum core **20** longer than the plate core **140** is prevented even if the first cured-adhesive portion **164** and the second cured-adhesive

portion 166 protrude to the outside of the plate core 140. Accordingly, with the coil device 110, it is possible to improve the bondability between the plate core 140 and the drum core 20 while suppressing external dimensional deviation. The other features and effects of the coil device 110 are similar to those of the coil device 10. 5

10,110:coil device

74: first electrode terminal

76: second electrode terminal

What is claimed is:

1. A coil device comprising:

a drum core, the drum core comprising:

a first flange portion having a first flange surface;

a second flange portion having a second flange surface;
and

a winding core portion disposed between the first and
second flange portions;

a coil wound around the winding core portion;

a plate core connected to the first flange surface at a first
direction side and the second flange surface at the first
direction side, the plate core comprising:

10

a first projecting portion protruding toward the first
flange surface and having a first flat surface facing
the first flange surface;

a second projecting portion protruding toward the sec-
ond flange surface and having a second flat surface
facing the second flange surface;

a first wall surface extending from the first flat surface
in a direction away from the first flange surface, the
first wall surface having a first inner wall surface
extending from the first flat surface at a side close to
the second flat surface; and

a second wall surface extending from the second flat
surface in a direction away from the second flange
surface, the second wall surface having a second
inner wall surface extending from the second flat
surface at a side close to the first flat surface;

a first electrode terminal provided on the first flange
portion, one end portion of the coil being electrically
connected on the first electrode terminal;

a second electrode terminal provided on the second flange
portion, another end portion of the coil being electri-
cally connected on the second electrode terminal;

a first cured-adhesive portion bonding the first flange
surface and the first flat surface that is also in contact
with the first wall surface, the first cured-adhesive
portion being in contact with the first inner wall sur-
face; and

a second cured-adhesive portion bonding the second
flange surface and the second flat surface that is also in
contact with the second wall surface, the second cured-
adhesive portion being in contact with the second inner
wall surface,

wherein the drum core and the plate core are connected by
abutting and bonding the first flange surface against the
first flat surface and by abutting and bonding the second
flange surface against the second flat surface.

2. The coil device according to claim 1, wherein the plate
core includes metal particles.

3. The coil device according to claim 2, wherein the drum
core is a ferrite core.

4. The coil device according to claim 1, wherein a length
of the plate core is shorter than a length of the drum core
along a winding axis direction.
